UNITED STATES PATENT OFFICE.

THEODORE SINGERMAN, OF NEW YORK, N. Y.

SHADOWPROOF UNDERGARMENT.

Application filed September 8, 1925. Serial No. 55,012.

This invention relates to undergarments for ladies' wear and particularly to a combined petticoat and bloomers, especially adapted for use with the prevailing modes 5 of dresses and outer garments worn at this time.

As is well known, the fashionably dressed woman to-day has practically discarded petticoats and has adopted as a substitute 10 therefor, bloomers, slips, etc., all of which have certain advantages and some disadvantages.

I have provided in my invention a garment which can be made of any suitable 15 material, and in any size, with such ornaments as may be desired, and at a cost that will enable the manufacturer to put out a line at both low and high prices.

The construction is such that the garment 20 will fit snugly, but comfortably, at the waist and knee, and is also what has come to be known as shadow proof, which is an important requisite when the outer garment is of light, sheer, or partly transparent material.

An important feature in this construction 25 consists of the form and method of attachment of the apron members to the body of the garment, as there is no double thickness 30 of material around the waist, over the hips or down the sides of the bloomer legs. Such double thicknesses are always objectionable for many obvious reasons.

It is also obvious that the elastic cuffs at 35 the bottom of the bloomer legs could be omitted if desired, and that the said lower ends or bottoms could be left freely open with openings on the sides of the said legs.

Other advantages and a detailed description 40 are set forth in the following specification, and shown in the accompanying drawing, which is a perspective view, with one of the aprons or petticoat members turned back to show how the other apron is positioned. As shown, the garment is alike 45 back and front, and therefore reversible in use.

It consists of a body 1, with an elastic 50 waist band 2, and bloomer legs 3—3, in the

lower extremity of which, elastic cuffs 4—4 are provided. On both the front and rear 55 of the garment, shadow proofing panels 5—5 are attached on the line 6. These shadow proofing panels are attached to the garment at points between the waist line 55 and crotch, and are of less width than the garment, whereby unnecessary bulkiness is eliminated, there being only a single thickness of material around the abdomen, hips, and small of the back, whereby a slim and 60 65 stylish effect is produced. The garment is thoroughly shadow proof between the legs, and yet is of light weight and comfortable to wear. In cases where heavy material is used, it would be possible, if desired, to dispense with one of the aprons, and use 65 only one of the same.

From the foregoing, it will be seen that this article can be elaborately decorated or embroidered, to present an attractive appearance.

I claim:

1. A shadow proof ladies undergarment comprising a pair of bloomers, and a shadow-proofing panel having its top edge 75 attached to the bloomers at a point between the waistline and crotch thereof, the panel being of less width than the garment, the sides of the panel below the crotch being free from the bloomers, whereby the garment is shadow-proof between the legs, and has only a single thickness of material 80 around the hips and waistline.

2. A shadow proof ladies undergarment comprising a pair of bloomers, and shadow-proofing panels attached to the front and rear of the garment at points between the waistline and crotch, the panels being of less width than the garment, the sides of the panel below the crotch being free from 90 the bloomers, whereby the garment is shadow-proof between the legs, and has only a single thickness of material around the hips and waistline.

In testimony whereof I have affixed my 95 signature.

THEODORE SINGERMAN.
